DESIGN FOR AN EMBROIDERED NET

Jack J. Blackstone, New York, N. Y.

Application November 2, 1936, Serial No. 65,635

Term of patent 3½ years

To all whom it may concern:

Be it known that I, Jack J. Blackstone, a citizen of the United States of America, residing in the city of New York, county of New York, and State of New York, have invented a new, original, and ornamental Design for an Embroidered Net, of which the following is a specification, reference being had to the accompanying drawing, forming part thereof.

The figure of the drawing is a plan view of an embroidered net showing my new design.

The design unit is contained between the broken lines, which unit is repeated in regular succession, as indicated by the extensions beyond the unit boundaries.

I claim:

The ornamental design for an embroidered net substantially as shown and described.

JACK J. BLACKSTONE.
